UNITED STATES PATENT OFFICE.

WILLIAM H. RANKIN, OF WALTHAM, AND HENRY R. MARSH, OF CANTON, MASSACHUSETTS, ASSIGNORS TO RANDOLPH CROMPTON, OF WORCESTER, MASSACHUSETTS.

WEFT-REPLENISHING LOOM.

Application filed September 21, 1920. Serial No. 411,788.

To all whom it may concern:

Be it known that we, WILLIAM H. RANKIN, a citizen of the United States, residing at Waltham, in the county of Middlesex and 5 Commonwealth of Massachusetts, and HENRY R. MARSH, a citizen of the United States, residing at Canton, in the county of Norfolk and Commonwealth of Massachusetts, have invented a new and useful Improvement in 10 Weft-Replenishing Looms, of which the following, together with the accompanying drawings, is a specification.

Our invention relates to that class of looms employing shifting shuttle boxes containing 15 shuttles having filling differing in color and material and also employing a filling feeder or magazine with filling carriers having filling corresponding to the filling used in the different shuttles contained in the shifting 20 shuttle box.

Various control devices have heretofore been employed for coordinating the shifting movement of the shuttle boxes with the mechanism controlling the movement of the 25 magazines, so that filling carriers having the proper kind of filling will be transferred from the magazine to the active shuttle. Such prior devices have usually operated to move the magazine upon the substantial 30 exhaustion of the filling in the active shuttle and have employed various more or less complicated mechanisms in order to obtain the desired results.

By our invention we propose to provide a 35 loom of the above described type with an improved type of control device, whereby the magazine containing the filling carriers will always be turned in the same direction upon the occurrence of each shifting movement of the shuttle box, irrespective of the amount of filling in the active shuttle. In this way a filling carrier with the proper kind of filling is always in place to be transferred to the shuttle upon the ejection of a 45 filling carrier from the shuttle carrying a given kind of filling. Our device is extremely simple in construction and positive in its operation, so that there is no possibility of the wrong kind of filling being transferred 50 to the shuttle. These and other advantageous features of our invention will hereinafter more fully appear, reference being had to the accompanying drawings, in which—

Fig. 1 is a view in side elevation of a weft 55 replenishing loom embodying our invention.

Fig. 2 is a front view of the loom shown in Fig. 1.

Figs. 3 and 4 are detail views showing our improved form of magazine.

Similar reference characters refer to similar parts in the different figures.

Referring to Fig. 1, the loom comprises a frame 1 carrying a crank shaft 2 and a cam shaft 3 connected to each other by gearing 4, in the usual manner. A lay 5 is connected to the crank shaft 2 by connecting rods 6 and is provided with a pair of movable shuttle boxes 7 and 8. The shuttle boxes 7 and 8 are attached to a shifting rod 9 that is connected by linkage 10 to one arm of a shifting lever 11. The lever 11 is pivotally mounted on a rocker shaft 12 and its other arm is connected to a shaft 13 by means of a crank 14 and link 15, so that rotation of the shaft 13 will impart an oscillating movement to the lever 11.

An intermittent gear 16 is mounted on the shaft 13 and is provided with a plurality of sets of teeth 17 and 18, each series being separated from each other by a space. A 80 pair of oppositely disposed sliding dogs 19 and 20 are arranged to be alternately moved into the spaces between the teeth 17 and 18 by means of a shifting arm 21. The arm 21 is connected to a control lever by means of a rod 23, so that movement of the lever 21 in either direction of rotation about its pivotal point 24 will cause one of the dogs 85 19 and 20 to be moved into the space between the teeth of the gear 16. The lever 22 is adapted to ride upon a chain 25 carried on a sprocket wheel 26. The wheel 26 is mounted on a shaft 27 that is so connected to the driving mechanism of the loom that the wheel 26 is turned through the pitch of one 90 tooth for each beat of the lay 5. A plurality of rolls 28 are arranged in series on the link pins 29 of the chain 25, so that the lever 22 will be raised from the position shown when a series of rolls 28 pass thereunder. When 95 the lever 22 is in its lowest position, in contact with only the link pins 29 of the chain 25, the dog 19 is in the space between the teeth of the gear 16, so that it will be engaged by the teeth 30 of a disk 31 mounted on the cam shaft 3. The gear 16 will then be turned until the teeth 30 engage the teeth 18, whereby the shaft 13 is turned until the teeth 18 are disengaged from the teeth 30.

This movement will cause the lever 11 to be 110

moved into the position shown in dotted lines, thereby raising the shuttle box 7 into the position formerly occupied by the shuttle box 8.

5 The shuttle box 7 will remain in this position until the lever 22 is raised by engagement with the first roll 28 of a given series. Lifting of the lever 22 will cause the dog 20 to be moved into the path of 10 the gear teeth 30 and the resulting movement of shaft 13 will cause the shuttle boxes to be lowered. It is obvious that the shuttle boxes will remain in either of the positions just described for a period of time determined by the number of rolls 28 in each 15 series of the chain 25. Thus, if there are three rolls 28 in each series, the shuttle contained in the shuttle box 8 will be acted upon by the picker stick 32 for three successive beats of the lay 5, before the shuttle box 7 is moved into its operative position. The shuttle in the shuttle box 7 will then be acted upon by the picker stick for a number of beats corresponding to the number of 25 link pins 29 between the rolls 28. All of the parts described thus far form no part of our present invention, but are usual in looms of the class described, in which it is desired to use shuttles containing filling 30 carriers with different colors or kind of material. It is therefore not believed necessary to further describe the operation thereof.

The lever 22 is also connected to one arm 34 of a bell crank lever 35 by means of a link 36. A spring 37, connected to the arm 34, serves to hold the lever 22 in engagement with the chain 25. The other arm 38 of the bell crank lever is connected to a rack member 39 by means of adjustable rods 40. The rack member 39 is pivotally mounted on a slide 41 by means of a pin 42, and is connected at its upper end to a second rack member 43 that is also pivotally mounted at 45 44 upon an extension 45 of the slide 41. The rack members 39 and 43 are respectively provided with teeth that are adapted to engage the teeth of a spur gear 46. With the parts in the position shown, the teeth 50 of the rack member 43 are in engagement with the spur gear 46, but when the lever 22 is raised by the rolls 28, the turning of the bell crank lever 35 moves both rack members to the right about their pivots and 55 causes the teeth of the rack member 39 to engage the gear 46.

The slide 41 is provided with a bifurcated projection 47, the arms of which embrace a pin 48 carried at the end of the lever 11 60 beyond its point of attachment to the linkage 10. A spring 49 serves to hold the slide 41 and the lever 11 in their lower positions, as shown. When the lever 11 is turned about its pivot 12 by the turning of the

shaft 13 as previously described, the slide 41 65 is moved upwardly, thereby causing the pinion 46 to be turned by the rack 43. When, however, the shuttle boxes 7 and 8 are shifted by the next movement of the lever 22, the lever 22 also shifts the rack members 70 39 and 43 to the right to cause engagement of the rack member 39 with the pinion 46. Therefore, when the slide 41 is moved downwardly by the lever 11, the pinion 46 will be turned in the same direction of rotation 75 that it was turned when engaged by the rack member 43 in the upward movement of the slide 41. In this way, the pinion 46 is always turned in the same direction of rotation by the reciprocating slide 41, due 80 to its engagement first by one rack member and then by the other.

The pinion 46 is continuously in mesh with a spur gear 50 that is mounted on a shaft 51 extending beneath the breast beam 85 52 of the loom. Referring now to Fig. 2, the shaft 51 is provided at its other end with a pinion 53 that is connected by gearing 54 to a magazine 55. The magazine 55 comprises an end ring 56 that is provided 90 on its outer periphery with a plurality of gear teeth 57 in mesh with the gearing 54. The end ring 56 of the magazine is rotatably supported upon a hub 58 having a plurality of radial arms 59 respectively provided with notches 60 for receiving an annular projection 61 formed on the inner periphery of the ring 56. The hub 58 is rigidly mounted on a shaft 62 carried by a bracket 63 extending upwardly from the breast beam 52. The end ring 56 also serves to support the butt ends of a plurality of filling carriers 64, the small ends of which are supported by a plate 65. The plate 65 is carried by a hub 66 rotatably mounted on the shaft 62.

From the foregoing it is apparent that the magazine 55 is adapted to be turned by the shaft 51 each time that the rack slide 41 is moved by the lever 11, and that this turning movement will always be in the same direction of rotation, owing to the shifting rack members 39 and 43. It is also apparent that the magazine 55 will be turned through a predetermined angle each time that the shuttle boxes 7 and 8 are shifted from one position to another, or in other words, each time that the color or material of the filling is changed. Therefore, if the filling carriers 64 in the magazine be arranged alternately with respect to the nature of the filling thereon, it is apparent that the filling inserted in the active shuttle will always be the proper kind, for the magazine will be turned to present a different kind of filling to the shuttle each time that the shuttle boxes are shifted, irrespective of the degree of exhaustion of filling in the shuttle.

In this way the operation of the device is made independent of any complicated filling detecting mechanisms, for the magazine is turned through a predetermined angle, always in the same direction of rotation, each time that the shuttle boxes are shifted.

Other advantages of our invention lie in the particular construction of the magazine, which is extremely simple in construction.

10 The support of the end ring 56 by the arms 59 eliminates the heavy hub which has always heretofore formed a part of the magazine. This construction adapts itself readily to the use of external gear teeth on the ring, 15 which are directly engaged by the gearing from the shaft 51, thus eliminating the various devices which have heretofore been employed in connection with the central hub of the magazine for rotating the same. It 20 is apparent that our improved construction of the magazine substantially reduces the weight of the same and particularly adapts it for the positive gear drive which we employ for rotating the magazine.

25 While we have shown our invention as applied to a weft replenishing loom employing shuttle box shifting means of a particular type, it is not so limited, but may be as well employed in connection with looms 30 of the same type but differing therefrom in detail construction. We desire therefore that only such limitations be imposed thereon as come within the scope of the appended claims.

35 We claim:

1. In a loom, the combination with a lay provided with shifting shuttle-boxes, a set of shuttles having filling-carriers with different kinds of filling, and a filling-feeder holding 40 a plurality of filling-carriers with different kinds of filling, of means dependent upon each shifting of said shuttle boxes for turning said filling-feeder successively in the same direction of rotation, whereby the said 45 feeder is always in position for the transfer therefrom of a filling-carrier having filling corresponding with that in the active shuttle.

2. In a loom, the combination with a lay provided with shifting shuttle-boxes, a set of 50 shuttles having filling-carriers with different kinds of filling, and a filling-feeder holding a plurality of filling-carriers with different kinds of filling, of means for turning said filling-feeder through a predetermined angle 55 every time the shuttle-boxes are shifted, the said turning movement always being in the same direction of rotation.

3. In a loom, the combination with a lay provided with shifting shuttle-boxes, a set of 60 shuttles having filling-carriers with two different kinds of filling, a filling-feeder holding a plurality of filling-carriers with two different kinds of, alternately arranged, filling, of means dependent upon each shifting

of said shuttle-boxes for imparting a step-by-step turning movement to said feeder in the same direction of rotation.

4. In a loom, the combination with a lay provided with shifting shuttle-boxes, a set of shuttles having filling-carriers with two different kinds of filling, a filling-feeder holding a plurality of filling-carriers with two different kinds of filling, alternately arranged, of means dependent upon each shifting of said shuttle-boxes for imparting a step-by-step turning movement to said feeder in the same direction of rotation, whereby the said feeder is always in position for the transfer therefrom of a filling-carrier having filling corresponding with that in the active shuttle.

5. In a loom, the combination with a breast beam, a lay provided with shiftable shuttle-boxes at one end of the breast beam, means for shifting said shuttle-boxes and a rotatable filling-feeder at the other end of said breast beam, of means for turning the said feeder through a predetermined angle upon each operation of the shuttle-box shifting means, the said turning movement being always in the same direction of rotation.

6. In a loom, the combination with a breast beam, a lay provided with shiftable shuttle-boxes at one end of the breast beam, means for shifting said shuttle-boxes and a rotatable filling-feeder at the other end of said breast beam, of a shaft extending longitudinally across the breast beam and connected by gearing to said feeder, and means actuated on each operation of said shuttle-box 100 shifting means for imparting an intermittent turning movement to said shaft always in the same direction of rotation.

7. In a loom, the combination with a breast beam, a lay provided with shiftable shuttle-boxes at one end of the breast beam, means for shifting said shuttle-boxes and a rotatable filling-feeder at the other end of said breast beam, of a shaft extending longitudinally across the breast beam and connected 105 by gearing to said feeder, and a racking device actuated on each operation of said shuttle-box shifting means for turning said shaft always in the same direction of rotation.

8. In a loom, the combination with a breast beam, a lay provided with shiftable shuttle-boxes at one end of the breast beam, means for shifting said shuttle-boxes and a rotatable filling-feeder at the other end of said breast beam, of a shaft extending across said breast beam and connected at its ends to said feeder and to a shiftable racking device actuated on each operation of said shuttle box shifting means to turn said shaft always in the same direction of rotation.

9. In a loom, the combination with a breast beam, a lay provided with shiftable shuttle-

boxes at one end of the breast beam, means for shifting said shuttle boxes and a rotatable filling-feeder at the other end of said breast beam, of a shaft extending across said breast beam and connected at one end to said feeder, a rack device cooperating with the other end of said shaft for turning the same upon each operation of said shuttle-

box shifting means, and means for shifting said rack device for causing the rotational movement of said shaft to always be in the same direction. 10

Dated this seventeenth day of September, 1920.

WILLIAM H. RANKIN.
HENRY R. MARSH.
